CLAIM

The ornamental design for a scrubbing cleaning brush, as shown and described.

DESCRIPTION

FIG. 1 is a rear, top and right side perspective view of a scrubbing cleaning brush showing my new design;

FIG. 2 is a front, bottom and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the scrubbing cleaning brush where the scrubbing cleaning brush is in a configuration of use.

The broken lines in the drawings depict portions of the scrubbing cleaning brush that form no part of the claimed design.

1 Claim, 9 Drawing Sheets
